APPARATUS FOR CLASSIFYING SPHERICAL ARTICLES

Waldemar D. Kmentt, Akron, Ohio, assignor to
The E. F. Geodrich Company, New York, N. Y.,
a Corporation of New York

Application March 29, 1929. Serial No. 350,955

15 Claims. (Cl. 209—97)

This invention relates to apparatus for sorting spherical articles, such as bearing balls, billiard balls, tennis balls, golf balls and golf-ball centers or cores, according to their size.

5 The chief object of the invention is to provide improved automatic apparatus for classifying, according to diameter, a continuous succession of spherical articles. Another object is to provide apparatus of the character mentioned having a wide range as to the sizes of the articles it is adapted to classify. Other objects will be manifest as the specification proceeds.

10 Of the accompanying drawings:
15 Fig. 1 is an elevation of apparatus embodying my invention in its preferred form.

Fig. 2 is a section on line 2—2 of Fig. 1.

Fig. 3 is a section on line 3—3 of Fig. 1.

Fig. 4 is a section on line 4—4 of Fig. 3.

20 Fig. 5 is a section on line 5—5 of Fig. 1.

Referring to the drawings, 10 is a support or base structure, 11, 12 are respective posts rising therefrom, and 13, 13 are upright frame members mounted upon the base adjacent one side thereof. Mounted upon the upper ends of the posts 11, 12 is a journal bracket 14, and a vertical, non-rotatable shaft 15 is mounted with one end in the bracket 14 and its other end in the base structure 10. Journaled upon the 25 shaft 15 is a rotatable drum 16 which is slightly tapered toward its upper end, and has its upper end provided with a gear 17 meshed with a pinion 18. The latter is mounted upon the lower end of a vertical shaft 19 journaled in an annular boss 20 formed on the journal bracket 14, and the upper end of the shaft 19 is provided with a bevel gear 21 meshed with a similar gear 22 on one end of a horizontal drive-shaft 23 journaled in a pair of brackets 24, 25 rising 30 from the journal bracket 14. The shaft 23 is driven from a suitable source of power (not shown) by means of the pulley 26 and driving belt 27.

35 Disposed concentric with the shaft 15 and circumscribing the drum 16 for about half its circumference is an arcuate plate or shield 28 which is formed at one of its lateral margins with apertured radial hinge-lugs 28^a, 28^a by which it is pivotally mounted upon the post 12. 40 Each hinge lug 28^a is recessed to receive a frustoconical member 29 disposed with its tapered face tangential to the shaft 12 and having an axial threaded stem 30 extending through the lug and provided exteriorly thereof with a hand lever 31 mounted upon said threaded portion.

The arrangement provides a recess 32 between the drum 16 and the plate 28 which recess progressively decreases in width in a downward direction. The recess is adapted to receive spherical articles from above, and after said articles are engaged by the converging walls of the recess they are rotated by the rotating drum 16 and thereby impelled laterally toward the margin of the plate 28 opposite the margin on which the hinge lugs are formed. In the event of an article jamming so tightly in the recess as to exert excessive pressure against the drum and plate, the latter will swing on its pivot against the frictional pressure of the members 29 to relieve the strain on the drum and plate 45 before either is scored.

50 Articles are introduced into the recess 32 between the plate 28 and drum 16 through an aperture 33 in the journal bracket 14, and said aperture is partly surrounded by a raised flange 34 which assists in directing the articles into the aperture as the articles are periodically delivered thereto from a hopper presently to be described. Secured to the plate 28 below the aperture 33 is a baffle or ledge 35 which extends obliquely 55 downward and is so positioned that it receives the impact of the falling articles before they are engaged by the converging walls of the recess 32 and thus prevents the articles from wedging in the recess as they fall thereinto. The ledge 35 60 may be positioned at various elevations on the plate 28 when articles of different sizes are to be classified so that it will always intercept the articles before the latter is engaged by the converging walls of the recess.

65 Spherical articles in the recess 32 are propelled by the rotating drum 16 toward the free margin of the plate 28, at elevations corresponding to their respective diameters, the oversize and undersize articles being disposed respectively in higher or lower planes than articles of the proper diameter.

70 The variously classified spherical articles are received at the delivery side of the recess 32 by individual receptacles, and for so receiving the classified articles I provide a vertically adjustable arcuate slide 36 which is formed with a dove-tail groove 37 (Fig. 3) and mounted upon a complementary dove-tail guide 38 comprising a flange extending radially from the free marginal portion of the plate 28. The guide 38 is provided with a rack 39 and meshed therewith is a pinion 40 mounted upon a shaft 41 journaled in the slide 36 and provided with an operating hand-wheel 42. The curvature of the 75 80 85 90 95 100 105 110

slide 36 is concentric with the shaft 15, and the slide comprises, in effect, an extension of the plate 28. The concave surface of the slide 36 is formed with three generally parallel oblique 5 grooves 43, 44 and 45 which extend from the margin of the slide that abuts the plate 28, to the bottom margin of the slide. The arrangement of the grooves 43, 44, 45 is such that they intersect the respective orbits of the three classes 10 of classified articles, correct size, oversize and undersize, and are of such depth that the articles upon engaging the grooves lose their frictional engagement with the rotating drum 16 and drop by gravity to the lower ends of the grooves at 15 the bottom of the slide.

The vertically adjustable character of the slide 36 permits it to be raised or lowered to proper position when articles of different sizes are to be gauged. A gib 46, Fig. 3, is positioned between the interfitted dove-tail portions of the slide 36 and guide 38 and is engaged by one or more cap-screws 47 by which it is forced against the guide 38 to hold the slide at the desired 20 elevation.

25 For receiving the articles as they drop from between the drum 16 and slide 36, at the lower ends of the grooves 43, 44, 45, I provide respective downwardly inclined chutes 48, 49, and 50 mounted upon a vertically movable frame 51. The latter is formed with an apertured boss 52 by which it is slidably mounted upon the post 11, and a cable 53, secured to said boss and passing over a sheave 54, has its free end provided with a counterweight 55 for facilitating the moving of 30 the frame 51 to various elevations so that the receiving ends of the chutes 48, 49, 50 are positioned close to the bottom of the slide 36, beneath the ends of the grooves therein. A cap-screw 56 is threaded through the boss 52 and bears against the post 11 for supporting the frame 51 at various elevations. Respective 35 receptacles 57, 58, 59 are supported upon the frame 51 at the delivery ends of the gravity chutes 48, 49, 50 for receiving the classified articles.

45 Spherical articles, such as the balls 60, 60 are periodically introduced into the classifying mechanism from a hopper 61 mounted upon the upper ends of the frame members 13, 13. The 50 hopper 61 comprises a barrel-shaped structure provided with central end openings, such as the opening 62, Fig. 5, and is peripherally journaled for rotation on a horizontal axis within a set of rollers 63, 63 which are journaled upon an annular bracket 64 supported by the 55 frame members 13. Each roller 63 is formed with a waist portion adapted to accommodate an external gear ring 65 secured upon the middle of the hopper and meshed with a pinion 66 having driving connection, through its shaft 67, and a sprocket chain 68 with the driven shaft 23.

60 Internally the hopper 61 is provided at its relatively large middle portion with a circumferential series of obliquely-disposed pockets 69, 69, each of which is adapted to receive a single one of the balls 60 when in the low part of its orbit and to carry the ball upward as the hopper rotates and drop the ball into a delivery chute 65 70, 70, which is mounted upon a bracket 71, Fig. 5, on the journal bracket 14, and has its receiving portion extending into the hopper through the adjacent end opening thereof and has its delivery end positioned at a lower level 75 over the aperture 33 in the bracket 14.

In the operation of the apparatus, the several rotary parts being driven by the belt 27 and a supply of the balls 60 being placed in the hopper 61, successive balls are picked up by the respective pockets 69 of the hopper and discharged 80 therefrom into the chute 70, down which they roll by gravity and fall therefrom through the aperture 33, into the recess 32 between the plate 28 and the rotating drum 16.

The balls 60 fall freely in the recess 32 until 85 they strike the obliquely disposed ledge 35, down which they roll at slow speed and then pass off the lower end thereof, being almost immediately thereafter engaged by the converging walls of the recess 32 before they attain sufficient momentum to cause them tightly to wedge between said recess walls. The points at which the downward movement of the balls is arrested by the converging walls of the recess corresponds 90 to the diameters of the respective balls.

The rotation of the drum 16 causes the balls to rotate and feed circumferentially of the recess, and as their travel carries them under the slide 36 they selectively engage the several 100 grooves 43, 44, or 45 therein according to their elevation which corresponds to their respective sizes. Engagement with either of said grooves releases the balls from frictional engagement with the drum 16 and they fall by gravity to the bottom of the device, following their intercepting 105 groove to the respective chute 48, 49, or 50 which direct them into the proper receptacle 57, 58, or 59.

The apparatus is rapid and automatic in operation, and by varying the elevation of the slide 110 36 it can be adapted to classify balls of various diameters.

Modifications are possible within the scope of the invention as defined by the appended 115 claims.

I claim:

1. In apparatus for classifying spherical articles the combination of a pair of downwardly converging walls defining a recess of diminishing width, means for feeding articles into said recess wherein they are engaged by said walls at elevations in accordance with their respective sizes, and means for moving one of the walls laterally of the direction of convergence to remove the articles from the recess selectively according to their respective elevations.

2. In apparatus for classifying spherical articles the combination of a rotary member and a stationary arcuate member so arranged as to define a recess of diminishing width, means for driving the rotary member, means for feeding articles by gravity into said recess so that they are engaged by the walls thereof at levels in accordance with their respective sizes and are fed laterally to the margin of the stationary member, and means thereat for directing the articles to respective stations corresponding to said levels.

3. Apparatus as defined in claim 2 including 140 an obliquely disposed ledge mounted upon the stationary arcuate member in the path of the incoming articles.

4. In apparatus for classifying spherical articles the combination of a tapered rotary member, a stationary arcuate member concentric with the axis of the rotary member and spaced from the latter to provide a recess of diminishing width, means for driving the rotary member, means for feeding a succession of articles, by 145 150

- 5 gravity, into said recess whereby the articles are engaged by the rotary member at elevations in accordance with their respective sizes and stationary member and fed toward a margin of the latter, and means thereat for classifying the articles according to said elevations. 80
- 10 5. Apparatus for classifying spherical articles, said apparatus comprising a pair of converging walls defining a recess of diminishing width, means for feeding the articles longitudinally of the recess until they are engaged by the walls thereof at levels in accordance with their respective sizes, means for moving one of said walls laterally of the direction of wall convergence for feeding the articles laterally, at said levels, to remove them from the recess, and means intersecting the course of the articles for diverting them to respective stations corresponding to said levels. 85
- 15 6. Apparatus as defined in claim 5 including means for adjusting the diverting means longitudinally of the recess. 90
- 20 7. Apparatus for classifying spherical articles, said apparatus comprising a pair of converging walls defining a recess of diminishing width, means for feeding a succession of articles longitudinally of the recess so that they are engaged by the walls thereof at elevations in accordance with their respective sizes, means for feeding the articles laterally to the delivery side of the recess, and means secured to one of said walls and formed with a plurality of grooves disposed obliquely to the course of the articles for diverting them to respective receptacles corresponding to the said elevations. 95
- 25 8. Apparatus as defined in claim 7 in which the article diverting means comprises a slide and including means for adjusting its position with relation to the outlet of the recess. 100
- 30 9. Apparatus for classifying spherical articles, said apparatus comprising a tapered rotary member, means for driving the same, an arcuate stationary member concentric with the axis of the rotary member and spaced from the latter to define a recess of diminishing width, means for feeding a succession of articles longitudinally of the recess until they are engaged by the walls thereof whereby they are impelled laterally toward a margin of the stationary member, and an arcuate slide mounted upon the stationary member in continuation thereof and formed with a plurality of grooves which intersect the course of the articles, whereby the latter are permitted to move by gravity to respective stations. 105
- 35 10. Apparatus as defined in claim 9 in which the feed of the articles into the recess is proportional to the speed of the rotary member. 110
- 40 11. In apparatus for classifying spherical articles the combination of a pair of converging walls defining a recess of diminishing width, and means for feeding articles into said recess wherein they are engaged by said walls at elevations in accordance with their respective sizes, means for moving one of said walls laterally of the direction of wall convergence for feeding the articles laterally from the recess and selectively according to their respective elevations. 115
- 45 12. In apparatus for classifying spherical articles the combination of a pair of downwardly converging walls defining a recess of diminishing width, means for feeding a succession of articles by gravity into said recess wherein the respective articles are engaged by both of said walls to prevent further descent into the recess, means positioned between the walls of the recess for receiving the impact of the articles before they are engaged by the walls, and means for thereafter removing the articles from the recess. 120
- 50 13. In apparatus for classifying spherical articles the combination of a pair of converging walls of rigid material defining a recess of diminishing width, means for feeding articles into said recess wherein they are engaged by said walls at elevations in accordance with their respective sizes, means for thereafter removing the articles from the recess selectively according to their respective elevations, and means operable automatically by excessive wedging pressure of an article engaged by the walls to permit movement of one wall away from the other for relieving the excessive pressure. 125
- 55 14. In apparatus for classifying spherical articles the combination of a pair of converging walls of rigid material defining a recess of diminishing width, means for feeding articles into said recess wherein they are engaged by said walls at elevations in accordance with their respective sizes, means for moving one of said walls laterally of the direction of wall convergence to roll the article along the walls for removing them from the recess, means comprising a frictional mounting for one of said walls to permit movement of it away from the other wall under excessive wedging pressure of an article engaging the walls. 130
- 60 15. In apparatus for classifying spherical articles the combination of a pair of walls defining a recess of diminishing width, one of said walls being stationary and having a margin, means for moving the second wall with relation to the first, means for feeding articles into said recess so that they are engaged by said walls at levels in accordance with their respective sizes and are fed toward said margin of the first wall by the movement of the second wall, a ledge on the stationary walls adapted to receive the impact of the articles entering the recess before they are engaged by the walls of the recess, and means at said wall margin for selectively assorting the articles according to the levels at which they emerge from the recess. 135
- 65 70 75 80 85 90 95 100 105 110 115 120 125 130 135 140 145 150
